WRENCH

Filed April 26, 1927

UNITED STATES PATENT OFFICE

STANLEY C. NORTH, OF EASTWOOD, NEW YORK

WRENCH

Application filed April 26, 1927. Serial No. 186,670.

This invention relates to a new and improved type of adjustable wrench, particularly that type of wrench commonly called "open-ended" in which the jaw faces are in planes parallel with that of the wrench handle.

The main object of my invention is to provide a wrench in which the position of the jaw members with reference to each other may be varied easily and speedily by permitting unrestricted movement of one of the jaw members.

Another object of my invention is to provide a simple and convenient means for locking the jaw members in spaced relation.

Other objects and advantages relate to the details and form of the device, all as will more fully appear from the following description taken in connection with the accompanying drawings in which:

Figure 1 is a perspective view of my device. Figure 2 is a section, partially in elevation, at line 2-2 of Figure 1, and with part of the handle broken away.

Figure 3 is a section on line 3-3, of Figure 2.

Like numbers refer to like parts of my device, and in the description the parts will be referred to as they appear in the drawings.

The upper jaw member —1— having a flat under face adapted to engage a nut, carries on one side thereof a rearwardly and downwardly extending flange —2—, and on the opposite side a corresponding flange —3— of uniform size and shape. The rear of jaw member —1— is provided with a slot —4— extending from top to bottom of such jaw member —1— and of a width somewhat less than the distance between the flanges —2— and —3—.

A T-shaped movable member —5— is provided with a jaw member —6— extending forwardly from the lower part of movable member —5— and with its upper face of a size and shape with the flat under face of jaw member —1—. The rear face of movable member —5— carries a series of ratchet teeth —7, 7— throughout its length. The movable member —5— is slidably mounted in slot —4— and between flanges —2— and —3—

with the flat face of the jaw member —6— disposed to coact with the flat face of jaw member —1— and with the series of ratchet teeth —7, 7— projecting rearwardly.

The downward movement of movable member —5— is limited by pin —8— fixed in the front edge of flange —2— at the bottom thereof. A locking member —9— of approximately square section, carries on one longitudinal surface a series of ratchet teeth —10, 10— extending the length thereof. At opposite ends of the surface carrying the ratchet teeth —10, 10— are provided bottomed holes —11, 11— adapted to receive springs —12, 12— and balls —13, 13—. Locking member —9— is mounted between flanges —2— and —3— with the ratchet teeth —10, 10— extending forwardly towards ratchet teeth —7, 7— and between pins —14, 14— which are fixed in flanges —2— and —3—. A handle —15— having a flat forward surface and being of approximately rectangular section is pivotally mounted between flanges —2— and —3— by means of pivot pin —16— and positioned so that its flat forward surface abuts the rear of locking member —9— when the handle —15— is in a plane parallel with the planes of the nut engaging face of jaw member —1— and the locking member —9— is forced backward by the balls —13, 13— and springs —12, 12—.

It will be obvious that when the handle —15— points straight back from the opening between the jaw members —1— and —6— and the locking member —9— is pushed backwards away from the ratchet teeth —7, 7— the movable member —5— may be moved up and down at will, varying the distance between the jaw members —1— and —6—. When the jaw members —1— and —6— have been placed in the desired spaced relation, the handle —15—, as perhaps may best be seen from the dotted lines in Figure 2, may be moved up or down with reference to the jaw member —1— effecting a cam action through its forward end to force the locking member —9— forward and to mesh the ratchet teeth —10, 10— with the ratchet teeth —7, 7— thereby locking the movable member —5— in position.

Altho I have shown and described a specific construction and form of part as illustrative of an embodiment of my invention I do not desire to restrict myself to the exact 5 form, shape or arrangement of the parts, as various changes may be made within the scope of the appended claims.

I claim:

1. In an open ended wrench, a wrench body 10 having a projecting jaw at one end, a movable member having a jaw in opposed relation to the first mentioned jaw and having a series of ratchet teeth on the rear edge slidably mounted in the wrench body, a locking member having a series of ratchet teeth slidably mounted in the wrench body for movement into and out of contact with the movable member, a handle pivotally mounted in the wrench body, a cam surface on the end of the handle 15 for forcing the locking member into contact with the movable member when the handle is pivoted in one direction, and a second cam surface on the handle for forcing the locking member into contact with the movable member when the handle is pivoted in the opposite direction.

2. In an open ended wrench, a wrench body having a projecting jaw, a movable body having a projecting jaw on one edge and a series 30 of ratchet teeth on the other edge movably mounted in the wrench body, a locking member having a series of ratchet teeth on one edge movably mounted in the wrench body, a plurality of apertures in the locking member, a ball in each aperture, a spring in each aperture forcing the balls against the ratchet teeth of the movable member to normally hold the movable member and the locking member in spaced relation, a handle pivotally 35 mounted in the wrench body, a cam surface on the handle adapted to force the locking member into contact with the movable member when the handle is pivoted in one direction, and a second cam surface on the handle 40 adapted to force the locking member into contact with the movable member when the handle is pivoted in the opposite direction.

In witness whereof I have hereunto set my hand this 16 day of April, 1927.

STANLEY C. NORTH.
